UNITED STATES PATENT OFFICE.

CASPER ZIMMERMAN, OF ABERDEEN, SOUTH DAKOTA.

ATTACHMENT FOR TELEPHONE-RECEIVERS.

No. 820,463.

Specification of Letters Patent.

Patented May 15, 1906.

Application filed November 4, 1905. Serial No. 285,901.

To all whom it may concern.

Be it known that I, CASPER ZIMMERMAN, a citizen of the United States, residing at Aberdeen, in the county of Brown and State of South Dakota, have invented certain new and useful Improvements in Attachments for Telephone-receivers; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in attachments for telephone-receivers for muffling one of the ears of a person while the receiver is held to the other ear, and comprises a simple and efficient mechanism which may be easily and quickly applied to an ordinary receiver and as conveniently removed, if desired.

More specifically the invention comprises a flanged ring having a grooved circumference adapted to fit over the flaring end of a receiver and held thereon by friction and supporting a resilient strip to which is secured a flanged disk or cup having a fabric about the edge thereof to take up vibrations.

My invention consists, further, in various details of construction and arrangements of parts, which will be hereinafter fully described and then specifically defined in the appended claim.

I illustrate my invention in the accompanying drawings, in which—

Figure 1 is a perspective view showing the application of my device. Fig. 2 is a perspective view of the device detached from a receiver, and Fig. 3 is a sectional view through the part of the apparatus which attaches to the receiver.

Reference now being had to the details of the drawings by letter, A designates a receiver of the usual construction, and B is a resilient ring having a flange B' projecting from one face thereof with its outer circumference flush with the circumference of the ring. The opening in said ring is of smaller diameter than the diameter of the opening in the flange, and the inner circumference of said flange is concaved and adapted to fit over the flaring end of the receiver. A por-

tion of the inner face of said ring serves as a stop against which the end of the receiver contacts. The outer face of said ring is preferably covered with a fabric D of some material adapted to take up vibrations. Secured to the circumference of said flange is a resilient metallic strip E, which is adapted to partially surround the head of a person, and F is a cup made of any suitable material and to which one end of said resilient strip is secured. A strip of fabric K is fastened to the marginal edge of the flange of said cup for the purpose of taking up any vibration which might be transmitted from the receiver through the resilient strip.

In the application of my device when the receiver is placed to one ear of a person the cup may be adjusted over the other ear and entirely surround the margin of the ear with the edge of the flange of said cup resting in contact with the side of the head about the ear, thus securely keeping any sound from entering the ear thus protected with the cup and affording better conditions under which the person may hear the sounds transmitted over a telephone and through the receiver.

From the foregoing it will be observed that a simple and efficient device is afforded which may be easily and quickly attached to the end of a receiver and easily removed therefrom when desired.

Having thus fully described my invention, what I claim as new, and desire to secure by Letters Patent, is—

In combination with a telephone-receiver, a cup of pliable material with a fabric about the marginal edge thereof, a strap of resilient metal fastened to the bottom of said cup, one end of said strap being angled, a resilient ring fastened to said angled end, said ring having a flange upon one side thereof, the inner marginal outline of the opening in said ring being concaved and adapted to receive the flaring end of a receiver, said flange serving to prevent the receiver from passing through the opening in the ring, as set forth.

In testimony whereof I hereunto affix my signature in the presence of two witnesses.

CASPER ZIMMERMAN.
